INNERSOLE AND METHOD OF MAKING
THE SAME

Fred L. Ayers, Waltham, Mass.

Application February 4, 1947, Serial No. 726,335

11 Claims. (Cl. 36—22)

1

This invention relates to innersoles of that type wherein the inseam rib includes a reinforcing layer of material folded on itself, and reinforced by a lip integral with the innersole blank and folded inwardly and secured to the doubled reinforcing layer.

An object of the present invention is to so form the reinforcing layer that the folded portion has a strong inherent tendency to lie sharply inwardly, so that when the lip is cemented to it, the inherent tendency of the lip to lift the folded layer will be ineffective to do so, the resultant lip being still biased to extend inwardly at a sharp angle.

It is a further object of the invention to so form this lip that it is unnecessary to secure the folded portion in inwardly inclined position, as by cementing or stitching it to the remainder of the strip which is cemented to the face of the blank.

This application is a continuation-in-part of my application Serial No. 571,739, filed January 8, 1945, for Innersole and method of making the same, now Patent No. 2,419,871.

For a complete understanding of this invention, reference may be had to the accompanying drawing, in which

Figure 1 is a perspective view of an innersole embodying the invention.

Figure 2 is a detail sectional view on line 2—2 of Figure 1.

Figure 3 is a view similar to Figure 2, but showing the parts in an earlier stage of manufacture.

Figure 4 is a view similar to Figure 3, but showing a modification.

Figure 5 is a view similar to Figure 4, but showing the lip turned back and cemented to the reinforcing strip.

Figure 6 is a view similar to Figure 2 but showing a further modification.

Figure 7 is a view similar to Figure 5, but showing the modification similar to that of Figure 6.

Referring first to Figures 1, 2 and 3, an innersole blank 1 is inwardly channeled about its margin at 2 to form a lip 3. This channeling may extend entirely about the forepart of the shoe, and it may also extend through the shank, or entirely around the shoe, if desired. As shown in Figure 1, it extends through the shank, the heel portion being unchanneled.

To the channeled face of the blank, is then cemented a reinforcing strip 4, which is folded on itself to form a double layer comprising the layers 5 and 6 and a single layer 7. It will be noted that the layer 5 extends outwardly somewhat beyond the line of fold between the layers 6 and 7 and contacts with the face of the blank outwardly of the outer edge of the layer 6. The strip 4 is preferably cemented together in folded condition, the layers 5 and 6 being in contact

2

and the folded layer 7, as well as the extended portion 8 of the layer 5, is cemented to the face of the blank. This extension 8, cemented to the face of the blank, is of great importance since it acts to retain the layers 5 and 6 in their sharp inwardly inclined position. The lip 3 is then turned inwardly and cemented to the outer face of the layer 5 as shown in Figures 1 and 2. While the lip 3 would of its own tendency tend to raise the double layers 5 and 6, the attachment of the portion 8 to the blank actively resists any such tendency so that the resultant rib comprising the lip 3 and the layers 5 and 6 is biased to incline sharply inwardly and over the single layer 7 of the reinforcing strip. As a further reinforcement, a strip 10, as shown in Figure 6, may be cemented to the top or channel face of the feather 11 remaining when the lip 3 was raised, and to the outer face of this lip in its inwardly inclined and folded back position.

If desired, the outer portion of the layer 5 may be further extended outwardly than is shown in Figures 1, 2 and 3, to more or less overlie the lip 3. This is shown in Figure 4, the reinforcing strip then comprising the single layer 7, the double layers 6 and 5, and an outer single layer 15, this layer 15 being a prolongation of the portion 8 shown in Figures 2 and 3.

It will usually be found desirable to terminate the layer 15 somewhat short of the outer edge of the lip 3 so that the lip 3, at least its extreme edge, may be cemented directly to the layer 5, as this provides a somewhat better bond for the lip than if it be attempted to cement together the fabric layers 15 and 5. However, if desired, the layer 15 may be extended to the outer extremity of the lip 3. The lip 3, reinforced by the layer 15, may then be folded back and cemented to the double layers 5 and 6, as shown in Figure 5, and also, if desired, a further reinforcing strip 10 may be applied to the top face of the marginal feather of the blank and the lip as shown in Figure 7 in the same manner that the lip and reinforcing layer is reinforced by a similar strip 10 in Figure 6.

In these constructions, it will be noted that the reinforcing layer, which may well be of fabric, which is cemented directly to the top face of the blank and over which the lip is inwardly folded, is of such a construction that it is strongly biased to take its sharply inward inclination and that this cannot be overcome by any tendency of the lip of the blank to lift it from this position, and that no stitching or other means for attaching the double folded portion to the underlying single layer 7 is required to accomplish this.

From the foregoing description of certain embodiments of this invention, it should be evident that various changes and modifications might

be made without departing from its spirit or scope.

I claim:

1. The method of making an innersole, which comprises folding a strip lengthwise on itself in opposite directions at different widthwise locations to form a single thickness portion partly overlaid with a double thickness portion, the upper layer of said double portion extending beyond the lower layer, the confronting faces of said double thickness portion being cemented together, cementing said strip to one face of an innersole blank about and spaced inwardly from its margin and with its single thickness portion turned inwardly and said extension projecting outwardly, said blank being inwardly channeled about its margin to form a lip adjacent to said face, and turning said lip inwardly and folding and cementing it against the outer face of said double portion.

2. The method of making an innersole, which comprises folding a strip lengthwise on itself in opposite directions at different widthwise locations to form a single thickness portion partly overlaid with a double portion, the upper layer of said double portion extending beyond the lower layer, the confronting faces of said double portion being cemented together, cementing said strip to one face of an innersole blank about and spaced inwardly from its margin and with the single thickness portion extending inwardly and said extension projecting outwardly, said blank being inwardly channeled about its margin to form a lip adjacent to said face and a marginal feather, turning said lip inwardly and cementing it against the outer face of said double thickness portion, and cementing a layer of strip material to the exposed face of said lip and to the face of the marginal feather of said blank outwardly of said lip.

3. The method of making an innersole, which comprises folding a cement coated reinforcing strip on itself to form a double layer between single layer margins, said double layer being inclined sharply over one of said margins, securing said strip so folded to the face of an innersole blank channeled inwardly to form a lip and a feather beneath said lip, and with said double layer inclined inwardly and with said other margin overlying, secured to, and reinforcing said lip, and then turning said lip so reinforced inwardly and securing it to the outer face of said double layer.

4. The method of making an innersole, which comprises folding a cement coated reinforcing strip on itself to form a double layer between single layer margins, said double layer being inclined sharply over one of said margins, securing said strip so folded to the face of an innersole blank channeled inwardly to form a lip and a feather beneath said lip, and with said double layer inclined inwardly and with said other margin overlying, secured to, and reinforcing said lip, then turning said lip so reinforced inwardly and securing it to the outer face of said double layer, and then cementing a reinforcing layer to the outer face of said lip and to the channel face of said feather.

5. An innersole comprising a blank channeled inwardly about its margin to form a marginal lip and a feather, said lip being reinforced with a layer of sheet material and turned inwardly and cemented to a double portion of said sheet material secured to the lip face of the blank and inclined inwardly, the stitch securing rib formed

by said lip and sheet material being sharply inwardly inclined and having an inherent tendency to remain in such inclined position.

6. An innersole comprising a blank channeled inwardly about its margin to form a marginal lip and a feather, said lip being reinforced by a layer of sheet material and turned inwardly and cemented to said sheet material folded on itself to form a single layer and a double layer inclined inwardly from the line of fold, said lip being cemented against said double layer, the stitch securing rib formed by said lip and sheet material being sharply inwardly inclined and having an inherent tendency to remain in such inclined position, and a reinforcing layer secured to said feather and to said inwardly turned lip.

7. An innersole comprising a blank channeled inwardly about its margin to form a marginal lip and a feather, said lip being reinforced by sheet material and turned inwardly and cemented to a double portion of a strip of sheet material secured to the lip face of the blank and inclined inwardly, the stitch-receiving rib formed by said lip and sheet material having an inherent tendency to lie sharply inwardly inclined.

8. An innersole comprising a blank channel inwardly about its margin to form a marginal lip and a feather, said lip being reinforced by sheet material applied to its outer face and turned inwardly and cemented to a double portion of a strip of sheet material secured to the lip face of the blank and inclined inwardly, said lip reinforcement comprising a portion of said strip, the stitch-receiving rib formed by said lip and sheet material having an inherent tendency to lie sharply inwardly inclined.

9. An innersole comprising a blank channeled inwardly about its margin to form a marginal lip and a feather, said lip being reinforced by sheet material applied to its outer face and turned inwardly and cemented to a double portion of a strip of sheet material secured to the lip face of the blank and inclined inwardly, said lip reinforcement comprising a portion of said strip, and a layer of strip material cemented to the outer face of said lip and to the channel face of said feather.

10. The method of making an innersole, which comprises securing a strip comprising a single layer and a double layer inclined sharply over said single layer to one face of an innersole blank channeled inwardly to form a lip and with said double layer projecting inwardly from the root of said lip and the upper of said double layers extending outwardly beyond the lower layer and directly secured to said blank, and then folding said lip inwardly and securing it to the outer face of said double layer.

11. The method of making an innersole, which comprises securing a strip comprising a single layer and a double layer inclined sharply over said single layer to one face of an innersole blank channeled inwardly to form a lip and a feather and with said double layer projecting inwardly from the root of said lip and the upper of said double layer extending outwardly beyond the lower layer and overlying and directly secured to said blank, then folding said lip inwardly and securing it to the outer face of said double layer, and then cementing a reinforcing layer to the outer face of said lip and to the channel face of said feather.
